UNITED STATES PATENT OFFICE.

JOHN C. SCHILLING, OF AVOCa, IOWA.

DOOR OR SASH VISE.

1,280,118.

Specification of Letters Patent. Patented Sept. 24, 1918.

Application filed August 27, 1917. Serial No. 188,449.

To all whom it may concern:

Be it known that I, JOHN C. SCHILLING, a citizen of the United States, residing at Avoca, in the county of Pottawattamie and State of Iowa, have invented certain new and useful Improvements in Door or Sash Vises, of which the following is a specification.

This invention relates to improvements in door, blind or sash vises and has for its main object the provision of a device for the use of carpenters or joiners, facilitating the holding of door, blinds, or the like, on edge when joining or fitting them for the frames.

Another object of this invention is to provide a device of the character described with minimum of parts and maintaining a maximum of efficiency, thus creating a vise of simple and economical construction.

With this and other objects in view, the invention consists in the construction, combination and arrangement of parts as will hereinafter be described and claimed.

Reference is to be had to the accompanying drawings forming part of this specification, in which like reference characters, indicate corresponding parts throughout the several views, and in which—

Figure 1 is a plan view of this invention,

Fig. 2 is an edge view of the same,

Fig. 3 is a view on the line 3—3 of Fig. 1, and

Fig. 4 is a view on the line 4—4 of Fig. 1.

This invention consists of an upper member 5 and a lower member 6 pivotally connected together by means of a pivot pin 7 passing through registering openings in the two members. The opening 8 in the upper or clamping member, indicated by the dotted line in Fig. 1, is elongated providing a means of adjusting the members to hold doors, blinds, or other such articles of various thicknesses, while the opening 9 in the lower member is screw-threaded to receive the threaded portion of the pivot pin. The upper portion of the pivot pin is smaller in diameter than the width of the elongated slot so as to allow free movement of the upper member. After the article has been set, the pin is tightened, thus holding the members in their proper relation.

Each of the members 5 and 6 is provided

with an up-turned end, which extends laterally and in oblique relation thereto, forming jaws 10, between which an article 11, indicated by the broken lines, is held on edge so that an operator may work thereupon to the best advantage. It is to be understood that these jaws are to be of sufficient size to firmly hold the article clamped therebetween.

The device is screwed to the floor or bench by passing a fastening element 12, through openings provided in lateral wings 13 formed on the lower member 6 adjacent one end thereof. The lower member 6 also is provided at its opposite end with an up-turned ear 14 which preferably is formed integral therewith. This member 14 serves as a stop for the upper member 5, when the jaws are widest apart, so that the jaws will be practically parallel with the upper member, when the upper member is against said stop.

The upper member 5 extends somewhat beyond the member 6 so as to provide a space between it and the support so that the fingers of the operator may pass under it to attain a grip on the end 15, which serves as an operating handle in causing the clamping action of the jaws.

In using the vise, the jaws are separated to the fullest extent and the article to be held therebetween is placed in engagement with the jaw on the lower member, and then the upper member is adjusted so that its jaw firmly grips the opposite side of the article. The article is placed between the jaws and the upper lever 5 is swung on the pivot pin 7, which is then tightened, thus securely holding the article preventing it from falling.

Although but one form of this invention has been described, it is to be understood that I may make such minor changes in construction and arrangement of parts as may be found expedient in the practical usage of this invention.

What I claim is:

A device of the character described comprising a pair of pivoted members having jaws, the upper member having its terminal extending beyond the terminal of the other and forming a gripping element, the lower

member carrying an upturned extension for limiting the movement of the said upper member, said jaws being in parallel relation when the upper member is against said extension, and lateral arms formed on said lower member for rigidly securing the device to a support.

In testimony whereof I affix my signature in presence of two witnesses.

JOHN C. SCHILLING.

Witnesses:

A. C. MEITZEN,

FRED C. SIMONSEN.
